SUSIE L. CAMPBELL, OF MAMARONECK, NEW YORK.

SEAT PROTECTOR.

Application filed December 1, 1922. Serial No. 604,238.

My invention relates to improvements in seat protectors such as are used on toilet seats for purposes of cleanliness and to prevent contamination or infection of a person using such seat. Heretofore protectors of this sort have been open to objections. They have either been too expensive, or too fragile. For a protector of this kind it is necessary that it be cheap so that it can be 10 once used and destroyed; it must be constructed so that it will not readily tear, or else its purpose will be nullified; and it should be of soft paper which will readily pass off with the waste water of the toilet. 15 When attempts have been made to make protectors of the kind described so as to meet the last named conditions, they have generally been made with a part of the surface plain, and this plain part having no elasticity, is almost certain to tear and make the protector useless. I have found, however, that by making the protector of soft paper so as to approximately fit the seat, and pleating the protector entirely across 20 the paper, that is making it in numerous little folds, the noted objections are eliminated, and the paper is given so much elasticity that it will readily adapt itself to the seat and person without tearing. When 25 made this way the protector can be of such soft paper that it will readily pass off with the waste water, and so cheap that it can be easily supplied for public and semi-public places. Furthermore, I find that by pleating 30 the protector transversely as stated, and entirely across, and then creasing it longitudinally, it will hold its place on the seat better even though the material is light and soft. In carrying out the invention, the 35 structure may be made in a long strip which can be pleated, and the ends pasted or otherwise secured together to form a structure which will fit the seat, or it can be cut out in the generally elliptical form desired from a piece of paper so that there will be no end to the material. This will be more clearly understood from the description 40 which follows.

Reference is to be had to the accompanying drawings forming a part of this specification, in which similar reference characters indicate corresponding parts in all the views.

Figure 1 is a perspective view of a strip

of material suitable for use in making the 55 protector.

Figure 2 is a broken plan view slightly in perspective, of the protector after it is pleated and the ends of the strip fastened together.

Figure 3 is a broken perspective partly in section, showing the complete protector as applied to a seat, and

Figure 4 is a plan and slightly perspective view of the protector cut out in the generally elliptical form desired.

In carrying out my invention I preferably use soft paper as stated, and the structure can be easily, cheaply and nicely made from a strip of paper 10, long enough to be 70 formed into the shape of the seat to which it is applied after it has been pleated, as presently described. The strip 10 is provided with numerous transverse folds or pleats 11 which extend entirely across the 75 strip, and the ends of the strip can be provided with adhesive material as shown at 12, so that when pleated and formed into the shape of the seat, the ends may be fastened together as shown at 13. The strip 80 can be easily pleated and formed this way by simply having the outer parts of the folds or pleats slightly wider than the inner parts, so that the lines of the folds will be radial to the centre of the structure. It 85 will be noted that these pleats 11 do not merge, but are spaced apart from each other, and are spaced wider at the outer part of the seat than at the inner part. This makes it easy to bring the body into the required 90 shape to fit the seat, and it also enables the pleats to retain their pleated shape when the structure is laid flat upon a seat, thus rendering light paper so elastic as to prevent it from being easily torn.

The protector can be used in the form shown in Figure 2, but I preferably give it a longitudinal crease or score as shown at 15, which causes it to rise up slightly along the generally middle portion of the strip, 100 as this causes the strip to fit better on the seat 14, and also fold up easier.

Instead of cutting the protector in the form of a strip 10, it can be died or cut out from a larger piece of material to the shape desired, as shown at 10^a in Figure 4, and the pleats 11 may be extended transversely 105 across the strip, forming the protecting part

as already described, and if desired the inner portion 16 can be bent inward and downward to make the protector better fit the seat,

- 5 The structure just referred to, and in fact any structure embodying the invention, can have an inner rim 10^b which will turn down over the inner side of the seat, thus fitting better, and making more perfect protection; and in this connection I would call 10 attention to the fact that the longitudinal crease 15 forms an inner rim, and this crease can be located at any desired point on the seat.
- 15 From the foregoing description it will be seen that I have devised an exceedingly simple and economical protector which can be folded into a very small compass, so that stocks of the protectors can easily be supplied 20 for public and semi-public places, or can be transported with facility and without encumbering the persons carrying them. It will also be understood that the material can be made antiseptic if desired.

- 25 It will be seen further that I entirely obviate the difficulties arising from structures of this kind which have part of their surface plain, and which therefore readily tear, because in the structure which I have devised 30 the various pleats will yield and so permit the protector to readily adjust itself without danger of tearing.

- It will be further understood that when the protector is formed of the strip 10, it is 35 much better to have the ends united, but it

may be used in strip form by simply laying the ends so that they will overlap when applied to the seat.

Attention is also called to the fact that the fabric of the protector which is preferably paper, can be made in many styles and in many compositions, without affecting the invention. For instance, the paper might be more or less water-proof to insure against dampness, and to make a more perfect protection. Attention is also called to the fact that where structures for this purpose have been made with plain surfaces, they are not only fragile, as pointed out, but they cannot be turned down to advantage to form an inner rim; whereas when the structure is pleated, even though the paper be soft, the inner rim can be turned down and will retain its position because of the stiffening effect of the pleats, and thus the structure can be made to fit any seat and afford the protection desired.

I claim:—

A seat protector of substantially the width of a toilet seat and adapted to rest thereupon, and formed of paper stock having pleats extending entirely across it, said pleats being so arranged that the lines of the folds of said protector are radial toward the center of the seat, and with a crease extending longitudinally of the protector and substantially midway of the sides thereof to shape said protector whereby the same is retained upon the seat.
